UNITED STATES PATENT OFFICE.

WILHELM GERBER, OF KREFELD, GERMANY.

MACHINE FOR STRETCHING HANKS OR SKEINS.

Application filed March 28, 1927, Serial No. 178,904, and in Germany October 30, 1926.

This invention relates to hank or skein stretching machines.

Machines for stretching real silk and cotton already known in the art which are used for smoothing and stretching the threads in hanks or skeins operate by the hank or skein being placed over two horizontal rollers, the upper one of which is constantly revolving while the lower one is alternately lifted towards the upper roller and then allowed to drop down. The hank is thus beaten by the lower roller while it is constantly moved in a path about its axis by the upper roller. The stretching operation formerly performed by hand and the adjusting of the threads in the hank so that all portions of the threads will be acted upon are thus mechanically simulated.

A machine of this description cannot be used for artificial silk, because the silk is moist when it passes over the machine and in this state it is easily injured. In consequence of the constant revolution of the upper roller during the up and down movement of the lower roller while the threads are at times slack and at other times taut, the threads are relatively displaced, causing variations in the sizes of the loops with consequent uneven tensions and rubbing contact of the threads, so that the threads become torn or otherwise injured.

I have discovered that these objections may be avoided by the provision of a machine whereby both rollers are held against revolving while the hank is being put on and removed, and both rollers also held against revolving during the up and down movement of the lower rollers, and by causing the rollers to revolve only when the hank lies stretched or taut between the rollers. It is moreover desirable that the extent of the swinging movement of the lower beater roller may be varied, as artificial silk is reeled in different lengths by different factories, and because it is necessary to beat one kind of silk more strongly than another.

The invention referred to here possesses all the qualities requisite for a machine for stretching of the yarn of all artificial silk without injury to the silk.

In the accompanying drawing showing by way of exemplification an embodiment of the invention,

Figure 1 is a side elevation of a duplex

type of machine constructed in accordance with the invention.

Figures 2 and 3 are sections on lines 2-2 and 3-3 of Figure 1.

A motor 1 drives, by means of a chain 2, a shaft 3 at each end of which there is arranged a double friction drive gear having diametrically disposed gear segments 4, the wedge-shaped circumferential faces of which engage the grooved friction pulleys 5 of corresponding cross section fixed on the horizontally arranged driving rollers 6. These rollers revolve intermittently whenever the segments 4 engage the pulleys 5, namely, twice on each revolution of shaft 3. The shaft 7 which is constantly driven by the motor 1 carries at each end a cam 8 which on different portions of its revolution lifts and then allows to drop the vibratory lever 9 fulcrumed on an eccentric gudgeon 24 and carrying a roller 10 to ride upon the cam. The lever 9 carries the freely revolving lower beating roller 11 which rises and falls with said lever, which is thus movable toward and from the companion driving roller 6. The force with which the roller 11 falls can be regulated by means of an adjustable balance weight 12 mounted on an arm 22 carried by the lever 9. The fall of lever 9 is cushioned and further regulated by an adjustable buffer spring 13.

The artificial silk hanks are placed on the driving rollers 6 and beater rollers 11 and stretched and smoothed by the up and down movement of the rollers 11. The cams 8 and the segments 4 are in such a position with respect to each other that during the up and down movement of the rollers 11 the rollers 6 are out of gear with the segments 4 and consequently remain stationary, i. e., do not revolve. For this purpose the gears 4 are mounted loosely on shaft 3 and locking wedges or devices 25 are provided for coupling them to or uncoupling them from said shaft.

A friction bevel gear 14 can be moved inward or outward by means of a hand lever 23. When moved inward the gear 14 engages a conical roller 15 mounted on the lever 9 so that it lifts the lever sufficiently to allow the cam 8 to pass freely under the roller 10, so that the roller 11 will be held elevated, and from being vibrated by the cam. This is the position of rollers 11 when the hanks are placed on the rollers 6

and 11 and removed from them, at which time the rollers 6 are caused to remain idle by operating the locking devices to uncouple gears 4 from shaft 3. It will be seen that 5 the sets of devices at opposite sides of the duplex machine can work independently of one another.

The operation is as follows: After the 10 hank has been placed on the idle rolls 6 and 11 the gear 4 is coupled to the constantly revolving shaft 3, the control-lever 23 is drawn out to free roller 11 for operation and the machine now works so that between 15 succeeding blows of the lower roller the upper roller revolves to shift the hank about the rollers during the time when the hank is stretched taut between the rollers. The hank is thus shifted only when the roller 11 is depressed and the roller 6 is rotated, thus 20 preventing any relative displacements of the threads of the hank and any injury thereto.

In order to vary the range of vibratory 25 movement of roller 11 the eccentric gudgeon 24 on which the lever 9 is mounted is turned to vary the height of the pivotal point of the lever, as will be readily understood. By this means the spacing between the levers may be changed for different sizes of hanks or to vary the beating and 30 stretching motion of roller 9 for any particular size of hank.

It is, of course obvious, that the invention 35 may be embodied in a single type of machine, i. e., a machine employing but a single set of working parts, or in a duplex machine, as shown, or in a machine having more than two sets of working parts, as desired.

It should be noted that the invention as 40 herein shown and described by way of illustration, may be modified and changed in various respects without deviating from the spirit of the invention, as expressed in the appended claims.

45 Having thus fully described my invention, I claim:—

1. In a hank stretching machine, a rotary 50 driving roller, a rotary and vibratory beating roller, and means for periodically rotating the driving roller when the beating roller is not vibrating and is at the limit of its distance from the driving roller, and for vibrating the vibrating roller when the driving roller is not rotating.

55 2. In a hank stretching machine, a rotary driving roller, a rotary and vibratory beating roller, means for periodically rotating the driving roller, and means for periodically 60 vibrating the beating roller, each of said means operating at a time period when the other is at rest.

3. In a hank stretching machine, a rotatable 65 driving roller, a rotatable and pivotally mounted beating roller vibratory on its pivot toward and from the driving roller,

means for periodically rotating the rotating roller, and means for periodically vibrating the beating roller, each of said means operating at time periods between intervals of 70 operation of the other.

4. In a hank stretching machine, a rotatable driving roller, a rotatable and pivotally mounted beating roller vibratory on its pivot toward and from the driving roller, means for periodically driving the driving 75 roller, means for periodically vibrating the beating roller, each of said means acting at time periods between time periods of action of the other, and means for shifting the pivot point of the beating roller so as to 80 dispose said roller at a greater or less distance from the driving roller.

5. In a hank stretching machine, a rotatable driving roller, a rotatable and vibratory beating roller pivotally mounted to 85 swing toward and from the driving roller, rotatable driving means for the driving roller operative on each rotation to twice impart a rotary driving motion to the driving roller, and means for vibrating the beating 90 roller between the driving movements of said driving means and while both rollers are not rotating.

6. In a hank stretching machine, a rotary driving roller, a rotatable and vibratory beating roller, a drive gear having a pair of driving elements operative on each half rotation of said gear to transmit driving motion to the driving roller, and means for vibrating the vibrating roller at periods 100 between the periods of action of said driving elements.

7. In a hank stretching machine, a rotatable driving roller, a rotatable and vibratory beating roller pivotally mounted for swinging movements toward and from said driving roller, means for periodically driving the driving roller, means for vibrating the beating roller between intervals of operation of said driving means, and means for swinging 105 said beating roller on its pivot and rendering it inoperative with respect to its vibrating means.

8. In a hank stretching machine, a rotatable driving roller, a rotatable and vibratory beating roller pivotally mounted for swinging movements toward and from the driving roller, means for periodically driving the driving roller, means for periodically 115 vibrating the beating roller between intervals of action of the first-named means, and means for rendering the driving means of the driving roller inoperative for a driving action thereon.

9. In a hank stretching machine, a rotatable driving roller, a rotatable and vibratory beating roller pivotally mounted for swinging movements toward and from said driving roller, means for periodically driving the driving roller, means for periodically vibrat- 125

ing the beating roller between intervals of operation of said driving means, and an eccentric support for the pivot of the beating roller adjustable to vary the position of said pivot and of said beating roller with relation to the driving roller.

10. In a hank stretching machine, a rotatable driving roller, a rotatable and vibratory beating roller pivotally mounted for swinging movements toward and from said driving roller, means for periodically driving the driving roller, means for periodically vibrating the beating roller between intervals of action of said driving roller driving means, 15 and means for shifting said beating roller toward the driving roller and out of engagement with its vibrating means.

11. In a hank stretching machine, a rotatable driving roller, a rotatable and vibratory beating roller pivotally mounted for swinging movements toward and from the driving roller, means for periodically driving the driving roller, means for periodically

ly vibrating the vibrating roller between periods of operation of said driving means, 25 means for varying the position of the pivot of the beating roller and the position of said beating roller with respect to the driving roller, and means for shifting the beating roller on its pivot toward the driving roller 30 and out of coaction with its vibrating means.

12. In a hank stretching machine, a frame, and sets of hank stretching devices on opposite sides of said frame, each including a rotatable driving roller and a rotatable and 35 vibratory beating roller pivoted to swing toward and from the driving roller, driving means for periodically actuating the driving roller, means for periodically vibrating the beating roller between intervals of operation 40 of the driving means, and means upon the frame providing a common source of power for the driving and vibratory means of the two sets of devices.

In testimony whereof I affix my signature.

WILHELM GERBER.
